(57) **CLAIM**

The ornamental design for a grooming apparatus, as shown and described.

DESCRIPTION

FIG. 1 is a perspective view showing a first embodiment of a grooming apparatus according to my design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof;
FIG. 7 is a bottom plan view thereof;
FIG. 8 is a perspective view showing a second embodiment of a grooming apparatus according to my design;
FIG. 9 is a front elevational view thereof;
FIG. 10 is a rear elevational view thereof;
FIG. 11 is a right side elevational view thereof;
FIG. 12 is a left side elevational view thereof;
FIG. 13 is a top plan view thereof;
FIG. 14 is a bottom plan view thereof;
FIG. 15 is an additional view of the first embodiment, shown with the dial in an alternative position;
FIG. 16 is an additional view of the first embodiment, shown with the dial in an alternative position;
FIG. 17 is an additional view of the first embodiment, shown with the dial in an alternative position;
FIG. 18 is an additional view of the first embodiment, shown with the dial in an alternative position;
FIG. 19 is an additional view of the first embodiment, shown with the dial in an alternative position; and,
FIG. 20 is an additional view of the first embodiment, shown with the dial in an alternative position.
The portions of the grooming apparatus shown in broken lines are included for the purpose of illustrating unclaimed portions of the grooming apparatus and form no part of the claimed design.

1 Claim, 11 Drawing Sheets
